[57] CLAIM

The ornamental design for a turnbuckle wrench head,
as shown and described.

DESCRIPTION

FIG. 1 is a top perspective view of the turnbuckle
wrench head showing my new design, the handle being
shown in broken lines for illustrative purposes only and
forming no part of the claimed design;

FIG. 2 is a side elevational view thereof, the opposite
side being a mirror image;

FIG. 3 is a top plan view thereof;

FIG. 4 is a bottom plan view thereof;

FIG. 5 is a front elevational view thereof;

FIG. 6 is a cross-sectional view thereof taken along line
6—6 in FIG. 2.
